Application August 30, 1937, Serial No. 161,644

4 Claims. (Cl. 88—79)

This invention relates to signals and more particularly to highway signals of the reflector type which are rendered luminous by reflecting light from an external source such, for example, as the headlights of a motor car, and an object of this invention is to provide an improved signal embodying the reflector principle. This application is a continuation in part of our application Serial Number 62,444 filed February 5, 1936.

10 Heretofore, signals of this type have usually taken the form of light-reflecting buttons generally arranged in roadside signs to spell out words or form diagrams or the like for directing traffic. Efforts to use such devices on the surfaces of 15 roadways to indicate dividing lines between the different lanes of traffic have not produced completely satisfactory results.

A further object of this invention is to provide a traffic signal of the reflector type constructed and arranged to be effectively employed on the surfaces of roadways for indicating the dividing lines between traffic lanes, although it will be hereafter apparent that the invention is also adapted to a wide variety of other uses.

25 These and other objects which will be apparent to those skilled in this particular art are accomplished by the present invention, one embodiment of which is shown for the purposes of illustration in the accompanying drawing in which

30 Fig. 1 is a top plan view of a signal constructed in accordance with one embodiment of this invention.

Fig. 2 is a transverse sectional view on the line 2—2 of Fig. 1 showing the manner of applying 35 it to a roadway.

Fig. 3 is a side elevation of the embodiment shown in Fig. 1, but with the guard member removed, and

40 Fig. 4 is a top plan view thereof.

The present invention provides a signal device which is particularly adapted, although not necessarily limited, to use on roadways for indicating dividing lines between different traffic lanes. In such use a plurality of devices are 45 arranged in spaced relationship along the dividing lines. Each device is constructed and arranged to reflect light from the headlights of motor cars approaching from either direction and on either side of the dividing line so that the incident rays are reflected back in the direction of an approaching car. Each device itself appears to be a brightly glowing light to the driver of an approaching car and the traffic lane formed by the line of lights compels the driver's 50 attention. The arrangement is such that as the

angle of incidence of rays changes with the approach of a car the angle at which the light is reflected is correspondingly changed with the result that the signal appears to the driver to glow brightly during the period of his approach from 5 a considerable distance away until he is substantially on top of it. The brightness of the signal results from the features of construction peculiar to the present invention.

The present invention comprises a unitary 10 transparent body, preferably of glass, having a light-refracting face of such formation as to refract incident rays of light from an external source such, for example, as automobile headlights, to a mirror surface located within the device and in turn so formed as to reflect the light received from said face back thereto in such a way that such face will refract or direct the reflected ray back in the direction of the external source. The construction and arrangement are 20 such that this function is fulfilled through relatively wide angles of incident rays. The device is preferably so formed as to be located in a bore formed in the roadway so that only the transparent refracting face is in the pathway of the 25 light rays, with the result that substantially the entire body portion is protected against injury. A relatively flat protective guard can be employed over the top of the device without interfering in any appreciable way with traffic. 30

The particular embodiment of the invention which has been chosen for purposes of illustration comprises a unitary, transparent body portion 5, preferably of molded glass, adapted to be located in a bore formed in the surface 6 of a 35 roadway as shown in Fig. 2. The top of the device may, if desired, be protected by a guard plate 7 having side arms 8 resting on the road surface and connected by a bridge member 9 extending across the center portion of the top of the glass 40 body 5 and formed with opposed cut away portions between the road engaging arms as shown in Fig. 1. For ease in shipping or handling, the guard and body portion may be connected together in any way desired. As illustrated, buttons 9' on each side of the body portion 5 extend through perforations formed in the lower ends of lugs formed on the guard and extending downwardly on each side of the device, see Figs. 2 50 and 3. The arrangement is such, however, that in use the guard does not rest on the body portion, but is spaced slightly therefrom so as not to contact directly therewith. The perforations in the downwardly extending lugs also serve to 55

anchor the guard in the roadway when the bore is filled with grouting material.

On each side of a central axial plane passing through the body portion 5 is an outer, transparent, light-refracting face 10 adapted to be located in the path of light from an external source. Each face 10 is so curved as to refract incident rays to an inner mirror surface 11 which, in the illustrated embodiment, is located on the opposite side of the axial plane passing through the body portion 5. Each mirror is so formed as to reflect such refracted rays back to the cooperating faces 10 where the emergent rays are again refracted and directed back in the direction of the external source of light.

The mirror surface can be formed in any of the various ways known to those skilled in the art. When the body portion 5 is made of glass, we prefer to form the mirror surface by spraying metal, such as aluminum, on the glass body while it is still hot from the molding operation, in the manner described, for example, in Stewart Patent No. 2,053,923, September 8, 1936. The metal coating thus formed adheres to and forms an integral part of the body portion. It provides an efficient mirror surface while the outer face of the coating forms a metal oxide which serves to protect the glass body and the mirror surface. We prefer to spray the entire body portion 5 below the transparent light-receiving faces 10 as well as the top 16 between the faces 10, as the coating forms a shock insulator when the device is placed in a roadway.

For the purpose of properly reflecting rays of light which are incident on the face 10 from a relatively high angle, as when headlights are close to the device, the mirror surface 11 has a lower portion curved in the vertical plane on a shorter radius than the upper portion thereof. This portion is illustrated as a mirror surface 12 which is offset from the main part of the mirror surface 11 for ease in manufacture, although it will be apparent that it may be formed as a continuation of the upper mirror face. Obviously, the mirror surface can be formed without any offset portions or with additional offset portions, if desired. In the drawing, each face 10 is curved in the horizontal on a radius of approximately $\frac{1}{8}$ inch, and in the vertical on a radius of approximately 1 inch. Hence the faces 10 are formed about different centers in at least one plane. This provides a most compact, efficient construction. The upper portion of the mirror surface 11 is shown as curved in the vertical on a radius of approximately $16\frac{1}{2}$ inches, while the lower portion 12 is curved in the vertical on approximately a $2\frac{1}{4}$ inch radius. In the horizontal, the mirror surface is curved on approximately a $2\frac{3}{8}$ inch radius.

The illustrated embodiment includes a base 13 which is merely provided for ease in molding but is not necessary to the successful operation of the device.

As shown, the base has an upwardly facing surface 14 which, together with the stepped construction of mirror surface, provide shoulders engaged by the cement or the like used to fill in the bore in the roadway to lock the signal in place.

In operation, when employed to indicate dividing lines between traffic lanes or the like, any desired number of devices are located in spaced bores formed along the dividing line in a roadway. Each device will be placed so that the light-receiving faces 10 face in opposite directions along the roadway. Incident rays of light from

headlights approaching from either direction enter the signal through the light-refracting face 10 on the side facing the lights and are refracted downwardly to the opposite mirror surface 11 or 12 depending upon the angle of incidence. The mirror surface reflects the refracted ray back to the face 10 where the emerging ray is again refracted and directed back in the direction of the approaching vehicle so as to be clearly visible to the driver. The face 10 gives a brilliantly lighted effect. As the vehicle approaches and the angle of incidence changes, the angle at which the emergent ray is directed changes accordingly, due to the curvature and arrangement of the face 10 and mirror 11 and 12. Of course, each face 10 and mirror 11 functions independently of the other so that the device operates equally with light from either side or from one side only.

It will be apparent that the invention can be variously modified and adapted within the scope of the appended claims.

We claim:

1. A road marker comprising in combination a guard member and a light reflecting body member having flattened sides, the guard member extending across the top of the body member and having opposed cut away portions between outwardly extending road surface engaging arms and a pair of lugs extending downwardly from said arms and adapted to engage the flattened sides of the body member, the said body member being provided with two oppositely disposed light refracting faces positioned in the cut away portions of the guard member above the horizontal plane of the underside of the road surface engaging arms and arranged at an angle to said horizontal plane, and cooperating concave light reflecting surfaces formed in said body member below said horizontal plane, each said light refracting face being curved in two planes on different radii to refract and transmit light incident thereon at an acute angle to said horizontal plane downwardly and across the interior of said body member against an opposite and cooperating light reflecting surface which is also curved in two planes on different radii to reflect the transmitted light toward and through the opposed cooperating light refracting face, and a coating of light reflecting material covering the reflecting surfaces and the flattened sides of the body member.

2. A road marker comprising in combination a guard member and a light reflecting body member, the guard member extending across the top of the body member and having opposed cut away portions between outwardly extending road surface engaging arms and a pair of lugs extending downwardly from said arms and adapted to embrace the sides of the body member, the said body member being provided with two oppositely disposed convex light refracting faces positioned in the cut away portions of the guard member above the horizontal plane of the underside of the road surface engaging arms, and cooperating concave light reflecting surfaces formed in said body member below said horizontal plane, each said light refracting face being formed to refract a beam of light incident thereon at an acute angle to said horizontal plane and transmit it downwardly and across the interior of said body member against an opposite and cooperating light reflecting surface which is formed to reflect the transmitted light toward and through the opposed cooperating light refracting face, and a coating of light reflecting material cover-

ing the reflecting surfaces and the sides of said body member.

3. A road marker comprising in combination a guard member and a light reflecting body member, the guard member extending across the top of the body member and having a cut away portion between outwardly extending road surface engaging arms and a pair of lugs extending downwardly from said arms to embrace the sides 10 of the body member, the said body member being provided with a convex light refracting face positioned in the cut away portion of the guard member above the horizontal plane of the under- 15 side of the road surface engaging arms, and a cooperating concave light reflecting surface formed in said body member below said horizontal plane, said light refracting face being curved in two planes to refract and transmit light incident thereon at an acute angle to said horizontal plane downwardly and across the interior 20 of said body member against said light reflecting surface which is also curved in two planes to reflect the transmitted light toward and through the opposed cooperating light refracting face.
- 25 4. A light reflecting element for a road maker

formed of molded glass with oppositely disposed light refracting faces separated by a central depression on the top face adapted to receive the bridge portion of an associated road surface engaging guard member and having flattened sides adapted to be located between depending lugs on said guard member, said light refracting faces being so positioned on the element as to be above the horizontal plane of the road engaging surfaces of said guard member when the element 10 is attached thereto, and inner oppositely disposed light reflecting faces so positioned on the element as to be below said horizontal plane, each said light refracting face being formed to transmit and refract light incident thereon at an acute 15 angle to said horizontal plane downwardly and across the interior of said element against an opposite and cooperating light reflecting surface which is formed to reflect the transmitted light toward and through the opposed cooperating light 20 refracting face, and a coating of light reflecting material covering said reflecting surfaces.
